UNITED STATES PATENT OFFICE.

ANDREW TAYLOR, OF GOLDVILLE, SOUTH CAROLINA, ASSIGNOR TO CLINTON CAM COMPANY, OF CLINTON, SOUTH CAROLINA, A CORPORATION OF SOUTH CAROLINA.

BOBBIN-SKEWER.

1,239,139.

Specification of Letters Patent.

Patented Sept. 4, 1917.

Application filed June 12, 1916. Serial No. 103,141.

To all whom it may concern:

Be it known that I, ANDREW TAYLOR, a citizen of the United States of America, and a resident of Goldville, county of 5 Laurens, State of South Carolina, have invented certain new and useful Improvements in Bobbin-Skewers, of which the following is a full and clear specification.

This invention relates to that class of 10 skewers employed for holding bobbins in roving machines. In this type of skewer, as is well known, the skewers are journaled vertically in a creel, the upper end of the skewer being held loosely in a top bar and 15 the lower pointed end of the skewer being provided with a pointed head whose point rests in a cup or socket formed in or mounted on the bearing rail of the creel. The bobbin is slipped down over the skewer 20 and rests upon an annular shoulder positioned at the lower end of the skewer. An objection to this common form of skewer as now made is that when the skewer carrying the bobbin is accidentally dropped on 25 the floor, as frequently happens in handling the bobbin, the bearing point is broken and the wooden shaft of the skewer is sometimes shattered; it is one of the objects of my invention to provide the lower or bearing 30 end of the skewer with a device which will prevent such injury to the skewer when a loaded skewer is accidentally dropped.

Another objection to the common form of skewer is that by reason of the fact that it 35 is usually tenoned at its lower end and screwed into a socket in the pointed head, the staff of the skewer is not only weakened but is insecurely fastened in the head; it is a further object of this invention to obviate 40 this objection.

A further objection to the common form of skewer is that the pointed head is usually made of wood, and it has been found that this material is so light in weight that 45 occasionally a skewer will jump or be pulled out of the cup bearing in which the point of the head rests; a further object of the invention is to obviate this drawback, as more fully hereinafter set forth.

50 In the drawing:—

Figure 1 is a side elevation of a skewer provided with my improved point;

Fig. 2 is a vertical sectional view of the lower end of the skewer;

55 Fig. 3 is a view similar to Fig. 2 with the

parts disassembled, in position to be assembled;

Fig. 4 is a transverse section on the line 4—4 of Fig. 2; and

Fig. 5 is a view similar to Fig. 3, showing 60 the socket wedge formed integral with the head.

Referring to the drawings annexed by reference characters, *a* designates the usual wooden staff of the skewer, and *b*, the 65 pointed head thereof, the latter being made of metal and being provided in its upper side with a socket for the reception of the lower end of the staff. This socket is enlarged downwardly, and, in order to spread 70 the inserted end of the staff to lock it permanently in the socket, an upwardly-tapering conical wedge *c* is employed, this wedge, when the parts are assembled, bearing against the bottom of the socket and being, 75 by the insertion of the staff, forced up into the end of the staff, to thus spread the lower end sufficiently to enlarge it to fit against the downwardly-tapering wall of the socket. In this way, a permanent rigid coupling is 80 made between the head and the staff without weakening the staff and without employing glue or other fastening devices of an insecure nature. This form of connection between the staff and the head is made feasible by employing metal for the head, as the metal is sufficiently strong to prevent the forcible spreading of the lower end of the staff from splitting the head, as would be likely to be the case if the head were made 85 of wood or other material of slight strength.

Instead of making the wedge *c* separate from the head, it may be cast integral therewith, as shown in Fig. 5. The head is provided with an annular flange *d* to support 95 the bobbin, and the upper part of the head is rounded off to fit within the lower end of the bobbin, or is otherwise shaped. The lower part of the head is tapered downwardly to form the integral metal point *f*. 100

By employing metal to constitute the head, it will be observed that, in addition to giving to the head the strength necessary for a rigid attachment of the staff thereto in the manner above set forth, I 105 get the further advantage that the lower end of the staff is steadied or anchored by the increased weight provided by the metal head, thereby tending to prevent the bearing point *f* from jumping or being pulled out 110

of the usual bearing cup. The metal head also serves to prevent injury to the point of or the skewer staff in case a loaded skewer is accidentally dropped to the floor point downwardly, thereby doing away with another material source of trouble with this type of device.

A disadvantage with the present wooden head is that it gathers lint, thus resulting in occasionally breaking the thread and loss of time required for cleaning the accumulated lint from the head; this disadvantage is entirely done away with by employing a metal head, in view of the fact that the

surface of the metal is too smooth for the lint to adhere to.

Having thus described my invention, what I claim is:

In a skewer, a wooden staff; an all-metal head provided with a downwardly-enlarged socket in its upper side adapted to fit the staff at its upper end; and a wedge-shaped device in the bottom of the socket entering the lower end of the staff to spread the same to fit the enlarged portion of the socket. 25

In testimony whereof I hereunto affix my signature.

ANDREW TAYLOR.
